[57] CLAIM

The ornamental design for a carrying case cover for a sewing machine, substantially as shown and described.

DESCRIPTION

FIG. 1 is a perspective view of a carrying case cover for a sewing machine showing our new design;
 FIG. 2 is a right side elevational view thereof, the opposite side being a mirror image thereof;
 FIG. 3 is a rear end elevational view thereof; and
 FIG. 4 is a bottom plan view showing the interior thereof.
